UNITED STATES PATENT OFFICE.

JOHN J. COUGHLIN, OF DAYTON, OHIO, ASSIGNOR TO FOLLMER, CLOGG & CO., OF NEW YORK, N. Y., A CORPORATION OF NEW YORK.

SPRING OPENER FOR PILOT PARACHUTES.

Application filed July 23, 1928. Serial No. 294,693.

Pilot parachutes that are automatically opened by springing instrumentalities, should have their centre of gravity well below the sail. My present device is intended to 5 position the heavier parts of the parachute frame permanently below the sail and to secure other advantages that will appear from a perusal of the detailed portion of the specification. The device is simple, strong and not 10 likely to get out of order or to fail to operate.

Fig. 1 is an elevation of the device. Fig. 2 is a bottom view of the spring assemblage that opens the parachute when released. Fig. 3 is an elevation of a portion of the retainer 15 for the springs. Figs. 4 and 5 are views of parts of the retainer.

The arms, 1, spread apart when released. They have suitable means for attaching the sail to the arms, 1, such as the caps, 2 with 20 eyes, 12. They are attached to and are operated by the springing instrumentalities, and, in practice, one set of arms is integral with a spring, 6, and another with the spring, 8. In practice, these springs are positioned 25 at right angles to each other, the spring, 6, being contained within the spring, 8.

The arms, 1, 1, 1, 1, are spaced from each other and the direction of their outwardly springing movements of the ends carrying 30 the cap, 2, is regulated by the retainer that has a strong tying element such as the portion of cylinder, 4, placed preferably centrally within the coils of the springs, 6, and 8. To the tying element is securely attached 35 spacers that prevent the coil springs from turning. These project side-wise from the central tying element, and lie at the sides of the coils, 6, and 8. These spacers are very preferably the loops, 5, and 3, which prevent 40 the turning of the arms in any undesirable direction while leaving their desirable springing action entirely free. They also can act as a stop to control the width of the spread of the arms, 1, 1. These loop elements 45 enclose the sides of the springs, 6, and 8, and limit their rotation so that the arms, 1, 1, 1, 1, will be kept properly spaced from each other. They also keep the arms from going downward, keeping the upper ends of the

arms, 1, 1, 1, 1, always at substantially the 50 same level.

The detailed construction of this retainer which I prefer is as follows:—The loops, 5, 55 are soldered to the ends of cylinder, 4. As their ends have a long bearing on the face of the cylinder this makes the connection very strong. The cylinders have the apertures, 9, 9, through which pass the side walls of the loop, 3. In practice, I may assemble these last parts by passing the loop, 3, with the 60 part, 13, not yet bent into its final position, through the apertures, 9, 9, and then bending over the part, 13, and soldering it fast at 10. The part, 3, may be soldered to the cylinder 65 4, where it passes through the apertures, 9, 9.

While my device is a simple one, it can be seen that changes in detail may be made without departing from my invention.

I claim:

1. In a spring opener for pilot parachutes, a plurality of coil springs set one within the other and at angles with each other, in combination with upwardly projecting arms connected to and moved by said springs, and a centrally located retainer for said springs, having a tying element located within the coil springs, and looping elements secured to said tying element, each enclosing a side of the coil springs. 80

2. The device as described in claim 1, wherein the tying element is a cylinder to which the looping elements are secured. 75

3. The device as described in claim 1, wherein one of the looping elements is passed through apertures in the tying element and secured thereto. 85

4. In a spring opener for pilot parachutes, a plurality of coil springs set one within the other and at angles with each other, in combination with arms connected to and moved by said springs, and a centrally located retainer for said springs having a tying element located within said coils, and spacers projecting from the said tying element and positioned at the sides of said coil springs, and holding the same in position. 95

JOHN J. COUGHLIN.
